UNITED STATES PATENT OFFICE

ROBERT BACK, OF CHICAGO, ILLINOIS, ASSIGNOR TO THE WAHL COMPANY, OF CHICAGO, ILLINOIS, A CORPORATION OF DELAWARE

DESIGN FOR A FOUNTAIN PEN

Application filed September 23, 1929. Serial No. 32,838. Term of patent 7 years.

To all whom it may concern:

Be it known that I, ROBERT BACK, a citizen of the United States, residing at Chicago, in the county of Cook and State of Illinois, have invented a new, original, and ornamental Design for a Fountain Pen, of which the following is a specification, reference being had to the accompanying drawing, forming part thereof.

Fig. 1 is a front elevation of a fountain pen showing my new design in an open position;

And Fig. 2 is a similar view showing the same in a closed position.

I claim:

The ornamental design for a fountain pen substantially as shown.

ROBERT BACK.
